UNITED STATES PATENT OFFICE.

CARL BRENDL, OF TSCHUPACKOWKA, RUSSIA.

APPARATUS FOR THE PREVENTION OF SEASICKNESS.

SPECIFICATION forming part of Letters Patent No. 769,466, dated September 6, 1904.

Application filed April 6, 1903. Serial No. 151,302. (No model.)

To all whom it may concern:

Be it known that I, CARL BRENDL, Ph. Dr., factory director, a subject of the German Emperor, residing at Tschupackowka, in the Empire of Russia, have invented certain new and useful Improvements in Apparatus for the Prevention of Seasickness, of which the following is a specification.

The object of the present invention is to provide means for the prevention of seasickness, which consists in making the long movements of the ship when pitching, rolling, heaving, and setting less felt by the passenger by providing chairs, couches, or a whole platform, forming a part of the deck, and carrying said chairs or couches and giving them either by machinery or by the hand short up and down motions. In consequence of the long movements of the ship being thus changed into a great number of short motions which are constantly interrupted by short movements in an opposite direction the causes producing seasickness are counteracted. The devices for producing the shaking motions may vary.

25 In the accompanying drawings a few forms of devices are illustrated which serve for the intended purpose.

Figure 1 gives a view of chairs the seats of which are provided with shaking devices. 30 Fig. 2 shows a platform with chairs, the shaking motion being here given to the platform itself. Fig. 3 shows a couch for receiving the shaking motion by the hand.

Similar letters refer to similar parts throughout the several views.

35 In Fig. 1 the chairs *a* are provided with elastic seats *b*. From the seats cords, wires, or wire ropes *c* pass through openings *d* in the deck *e* over pulleys *f*, arranged below the deck, to a bar *g*, lying crosswise, to the seats of the chairs, and to which bar the ropes are fastened. This bar receives a to-and-fro motion in the direction of the arrows and causes, through an alternate pulling at and releasing 40 of the rope *c*, a shaking of the seats *b*. For a row of chairs standing side by side a long bar can of course be provided between the legs of the chairs, and to this bar a shaking motion, as just described, be given, or a motion in a vertical plane, which is then com-

municated to the chairs. The shaking motion can also be produced by vertical bars connected to the seats and raised at short intervals by a rotating shaft *S*, with a cam or an eccentric *S'*. An arrangement of this kind is 55 shown in Fig. 2. Here the chairs are standing on two platforms *h i*, which, being supported at *k*, are movable at their ends *l* in a vertical direction. The shaking motion is communicated to the platform *h* through a 60 vertical bar *m*, which is moved up and down in its longitudinal direction by suitable means, as described, and which is provided on the side of the other platform with a curved piece *n*, with which it presses from above upon a lever *p*, supported at *o*. The other end of the lever stands in communication with the platform *i* through a bar *q*, with turning joints at either end. On moving the bar *m* up and down not only the platform *h*, but also the 70 platform *i*, is moved up and down.

Instead of the bar *m* and the lever *q* a long plate may of course be made use of in order to give a shaking motion at one and the same time to broader platforms *h i*, with several 75 chairs, unless it should be more advantageous to use several bars *m* or levers *q* for such purpose. This can in all cases be arranged to suit the requirements and circumstances. Finally, the shaking motion can also be produced by the hand by pulling at or pressing on handles arranged above the chairs or couches *a*, which latter are resting on springs, as shown in Fig. 3. For the convenience of 80 travelers arm-chairs or inclined chairs as used 85 on board ship may be substituted for the chairs shown in the drawings. It can also be arranged that on the downward motion of the ship the upward shakes are quicker than the downward ones and, further, that at the rising 90 of the ship the contrary takes place in order to more effectively counteract the main or long movements of the ship.

What I claim as my invention, and desire to secure by Letters Patent of the United States, 95 is—

1. An apparatus for the prevention of seasickness, consisting of reclinatory means for the passenger arranged on board a ship, and means connected with said reclinatory means 100.

for imparting to the same a rapid reciprocatory movement for counteracting the long movements of the ship when rolling, heaving and setting for making said movements of the ship less felt by the passenger on said reclinatory means, substantially as set forth.

2. An apparatus for the prevention of seasickness, consisting of a platform arranged on board a ship, reclinatory means on said platform, and means connected with said platform for imparting to the same a rapid reciprocatory movement for counteracting the long

movements of the ship when rolling, heaving and setting, for making said movements of the ship less felt by the passenger on said reclinatory means, substantially as set forth. 15

In testimony that I claim the foregoing as my invention I have signed my name in presence of two subscribing witnesses.

CARL BRENDEL.
